DESIGN FOR A SLIDE FASTENER STRINGER

Morris Norkin, New York, N. Y., assignor to
Marvel Slide Fastener Corporation, New York,
N. Y., a corporation of New York

Application May 19, 1942, Serial No. 106,954

Term of patent 14 years

To all whom it may concern:

Be it known that Morris Norkin, a citizen of the United States and resident of New York city, in New York County, State of New York, has invented a new, original, and ornamental Design for Slide Fastener Stringers, of which the following is a specification, reference being had to the accompanying drawing, forming part thereof, in which:

Fig. 1 is a front elevational view of a slide fastener stringer embodying my new design;

Fig. 2 is a rear elevational view thereof; and
Fig. 3 is a top plan view.

The dominant features of the design are shown in full lines in the drawing.

I claim:

The ornamental design for a slide fastener stringer, substantially as shown and described.

MORRIS NORKIN.
